WERNER BUSCHBECK, OF BERLIN, GERMANY, ASSIGNOR TO TELEFUNKEN GESELLSCHAFT FÜR DRAHTLOSE TELEGRAPHIE M. B. H., OF BERLIN, GERMANY, A CORPORATION OF GERMANY

TUBE TRANSMITTER CIRCUIT ARRANGEMENT

Application filed May 28, 1929, Serial No. 366,582, and in Germany June 30, 1928.

This invention relates to thermionic devices and in particular to devices used in short wave communication.

An object of this invention is to provide a thermionic generator which will not radiate waves at frequencies other than the desired frequency.

Another object of this invention is to provide a novel thermionic signaling device in which means is provided to obviate the necessity of maintaining symmetrical capacity to ground effect between the circuits or portions thereof.

Other objects and advantages will become apparent from the following specification, and therefrom when read in connection with the drawing herein referred to and in which

Figure 1 shows one circuit arrangement of a thermionic device arranged in accordance with the present invention; while

Figure 2 shows a modification of the arrangement shown in Figure 1.

It has been found in practice that in circuit schemes of the kind illustrated in Figure 1, disturbing or stray waves are liable to be caused by the plate direct current supply lead A. This is due to the fact that the potentials prevailing across the terminals of condenser C_B connected between the filament 1 and oscillation circuit 2, 3, 4 connected to the anode 5 of tube O, are mostly higher than what would have to be expected according to theory. Inasmuch as both the plate end as well as the lower part of the oscillation circuit exhibit distributed capacitances to ground which are exactly alike only in rare cases, a compensating current liable to exceed the plate alternating current many times in value will flow by way of the blocking 40 condenser C_B instead of merely the pure ac-

tive current of the tube. The result is that this large current sets up disturbing potentials across the condenser C_B , and these potentials can be obviated, for instance, by renewed choking of lead A.

Another simple means according to the invention consists in connecting the current-supply choke-coil D not directly with C_B , but with a distinct condenser c which, as a matter of fact, passes only the small radio frequency current leaking off by way of D so that the direct current lead A is really united with a point which has no radio frequency potential to ground. This circuit arrangement is illustrated in Figure 2. Choking and damping of lead A will then no longer be necessary. The identical scheme may be adopted when the oscillation circuit with the condenser lead (potential divider) is connected in the grid circuit of the tube.

I claim:

Signaling means comprising, a thermionic tube device having a cathode and cold electrodes, an oscillation circuit comprising a capacity and an inductance connected in parallel, means connecting adjacent ends of said capacity and said inductance to a cold electrode, means for applying direct current potential to said cold electrode including a choke coil connected at one end to a point intermediate the terminals of said inductance, capacitive means for connecting a point intermediate the terminals of said parallel capacity to said cathode, and capacitive means for connecting the free end of said choke coil to said cathode, said last named capacitive means and connection being entirely separate from said first named capacitive connecting means.

WERNER BUSCHBECK.
